A. S. SMITH.
SUSPENDING APPARATUS FOR GEOGRAPHIC GLOBES.
APPLICATION FILED MAR. 26, 1915.

1,239,231.

Patented Sept. 4, 1917.

UNITED STATES PATENT OFFICE.

ALBERT S. SMITH, OF NEW YORK, N. Y., ASSIGNOR TO RAND, McNALLY COMPANY,
A CORPORATION OF ILLINOIS.

SUSPENDING APPARATUS FOR GEOGRAPHIC GLOBES.

1,239,231.

Specification of Letters Patent.

Patented Sept. 4, 1917.

Application filed March 26, 1915. Serial No. 17,163.

To all whom it may concern:

Be it known that I, ALBERT S. SMITH, a citizen of the United States, and a resident of New York city, in the county of New York and State of New York, have invented certain new and useful Improvements in Suspending Apparatus for Geographic Globes, of which the following is a specification.

10 This invention relates to suspending apparatus for geographic globes.

The principal object of this invention is to provide a suspending device for geographic globes which is simple in construction, and which admits of the ready manipulation and adjustment of the globe.

Further objects and advantages arising from the construction, arrangement, and combination of parts will more fully appear 20 from the following detailed description and the features of novelty will be particularly pointed out in the claims.

In the drawings—

Figure 1 illustrates a side elevation of 25 my improved suspending means, shown fastened to a wall, and Fig. 2 is a front elevation thereof.

Fig. 3 is a detail view on an enlarged scale of the segment from which the meridian ring is suspended.

Figs. 4 and 5 are cross sectional views taken respectively along the lines 4—4 and 5—5 of Fig. 3.

Referring particularly to the drawings, 35 the suspending device is preferably mounted on a base 10, which may be secured to a wall 11, or any other suitable support. Suitably fastened to the base is a clutch 12 through an aperture of which is inserted a vertical 40 rod 13. An arm 14 extending from the latter is provided with a hook 15 from which is suspended, through connections hereinafter more particularly described, the globe 16.

The rod 13 is normally held rigidly to the 45 base through the action of the clutch 12 impelled by the expansion spring 17 which causes the finger pieces 18 to diverge from each other. The clutch also serves as a guide for the rod in its vertical movement and 50 above the clutch is disposed a bracket 19 having an aperture through which the rod passes, and which also serves as a guide for the rod. The vertical rod may be readily adjusted to different positions by grasping a finger piece 20 provided at the lower

end of the rod and unclamping the latter by pressing together the finger pieces 18. Thus, when the pupils are required to use the blackboard, the globe may be very readily adjusted to a position above the blackboard, 60 leaving the space free and clear.

I will now describe the immediate suspending means of the globe which, as above stated, is hung from the arm 14. This consists of a segment 21 having a depending 65 hook 22 extending from each end. These hooks slidably engage the inner periphery of a meridian ring 23 in which is pivotally mounted at its axis the globe 16. Preferably, the distance between the upturned lip 70 22^a of the hook 22 and the inner overhanging surface 22^b thereof is approximately equal to the radial width of the meridian ring. Thus accidental disengagement is avoided. A saddle 24 fastened to the segment midway between the hooks and having a pair of shoulders 24^a formed therein which slidably engage the outer periphery of the meridian ring, serves as a guide for the latter when it is rotated within the hooks, 75 and thus further assists to retain the ring properly in position. Indicators 25 depending from the saddle on each side of the ring are provided for the graduations engraved or molded on the latter. The segment may 80 span an arc of 60° or 90° or more if desired, thus making it possible to swing the globe to any angle up to 45° or more, which is the most that will be found desirable in the practical use of the apparatus. 90

Upstanding from the saddle is an eye 26, and engaging the latter is a swivel 28, in which is pivoted a swivel hook 29. This hook may engage the hook 15 of the horizontal arm and suspend the globe with its 95 connections therefrom. When so suspended, the globe and ring may be readily manipulated in all directions. Thus, they may be raised or lowered by unclamping the vertical rod 13. By means of the swivel, they may 100 both be rotated on a vertical axis, the globe being so rotated independently of its own pivotal bearings within the ring.

It may sometimes occur during the adjustment of the vertical rod that the latter is 105 inadvertently released while the finger pieces 18 are being pressed toward each other. In that event, the rod being free to move would immediately drop so that the arm 14 would strike the bracket 19 with quite an impact. 110

To avoid this difficulty, a helical spring 27 is provided about the rod above the bracket. When the clutch is released, the arm will strike the spring instead of the bracket and 5 the shock of impact is thus taken up.

It will thus be seen that I have provided a suspending device which is simple in construction and efficient in operation, and which admits of the ready manipulation 10 and adjustment of the globe for all purposes desired. Means is provided for raising or lowering the globe to any convenient height, and to guard against shocks occasioned by the inadvertent dropping of the 15 vertical supporting rod suitable cushioning means is provided. Means is also provided whereby the globe and ring may be rotated about a vertical axis so that the rear of the globe and ring may both be readily turned 20 to the front whenever desired.

Having thus described my invention, I claim—

1. In a suspending device for globes, a graduated meridian ring in which the globe 25 is adapted to be pivotally mounted, a segment having a depending hook at each end provided with an upturned lip, said hooks engaging and securely holding the inner periphery of said ring, a pointer for the 30 ring located upon the segment, and rigid means for suspending said segment and means for vertically adjusting said suspending means.

2. In a suspending device for globes, a 35 graduated meridian ring in which the globe is adapted to be pivotally mounted, a segment having a depending hook at each end integral therewith, said hooks slidably engaging the inner periphery of said ring, a 40 saddle fastened to the segment midway between the hooks, said saddle having a pair of shoulders formed therein which abut the outer periphery of said ring and serve to guide the latter as it is moved through the 45 hooks, and an engageable portion, and means for suspending the segment from said engageable portion.

3. In a suspending device for globes, a graduated meridian ring in which the globe 50 is adapted to be pivotally mounted, a segment having a depending hook at each end integral therewith, said hooks slidably engaging the inner periphery of said ring, a saddle fastened to the segment midway be- 55 tween the hooks, said saddle having a pair

of shoulders formed therein which abut the outer periphery of said ring and serve to guide the latter as it is moved through the hooks and to help support the weight there- 60 of and of the globe, and means for suspending said segment, each hook being provided with an upturned lip, the distance between the lip and inner overhanging surface of the hook being approximately equal to the 65 radial width of the meridian ring.

4. A unitary portable apparatus of the character described comprising a globe and meridian ring in which said globe is pivotally mounted, means for suspending said 70 ring comprising a base attachable to a wall, a vertically movable rod adapted to be mounted upon said base and guided thereon, a horizontal arm extending from said rod, swivel connections between said arm and ring, and means mounted on said base for clamping said rod in its adjusted position. 75

5. A unitary portable apparatus of the character described comprising a globe and meridian ring in which said globe is pivotally mounted, means for suspending said 80 ring comprising a base, a vertically movable rod mounted upon said base, a horizontal arm extending from the rod, swivel connections between said arm and ring whereby the globe may be rotated vertically independently of the rod and arm, means mounted on said base for clamping said rod in its adjusted position, and means mounted on the 85 rod for absorbing the shock incident to the 90 inadvertent release of the rod.

6. In a suspending device for globes, a meridian ring in which the globe is mounted, a segment having a depending hook at each 95 end, said hooks engaging the inner periphery of said ring, a bracket, and means whereby said segment is rotatably connected to said bracket, said means comprising a saddle attached to the segment, an eye integral with said saddle disposed medially 100 at the top thereof, a swivel engaging said eye, and a swivel hook pivoted in said swivel.

Signed at New York city, in the county of New York, and State of New York, this 105 22nd day of January A. D. 1915.

ALBERT S. SMITH.
